[57] CLAIM

The ornamental design for a compression latch, as shown and described.

DESCRIPTION

FIG. 1 is a top, right side perspective view of a compression latch showing our new design;

FIG. 2 is a left side elevation view thereof, the right side being a mirror image of the right side;

FIG. 3 is a top plan view thereof;

FIG. 4 is a front elevation view thereof;

FIG. 5 is an enlarged bottom plan view thereof; and,

FIG. 6 is an enlarged rear elevation view thereof.
